UNITED STATES PATENT OFFICE.

BENJAMIN BROBST, OF COLUMBUS, OHIO.

WASHING-MACHINE.

SPECIFICATION forming part of Letters Patent No. 443,566, dated December 30, 1890.

Application filed August 5, 1889. Serial No. 319,793. (No model.)

To all whom it may concern:

Be it known that I, BENJAMIN BROBST, a citizen of the United States, and a resident of Columbus, county of Franklin, State of Ohio, 5 have invented a new and useful Improvement in Washing-Machines, of which the following is a full, clear, and exact description, reference being had to the accompanying drawings, making part of this specification.

10 My invention relates to improvements in washing-machines; and it consists of certain features of construction and combination of parts, as will be hereinafter described, and set forth in the claims.

15 Figure 1 is a view in perspective of a washing-machine illustrating my invention in which a portion of the side of the tub is removed, showing the detail of the central portion of the machine in cross-section. Fig. 2 is a 20 vertical sectional view. Fig. 3 is a perspective of the bottom or leg portion of the supporting-frame. Fig. 4 is a vertical sectional view taken through the same, showing the standard and cross-bar secured in position. Fig.

25 5 is a perspective view of a portion of the bottom of the tub, showing the manner of securing the connecting-rod thereto. Fig. 6 is a side elevation of the connecting-rod box; Fig. 7, a sectional view of same. Fig. 8 is a perspective of connecting-rod box and a fragment of the actuating-lever; Fig. 9, a plan view of lever bracket or support. Fig. 10 is a detail view of a modification of the pivotal support for the tub, and Fig. 11 is a similar 30 view of the connecting-rod O'. Fig. 12 is a vertical sectional view of the tub, showing the manner of supporting the false bottom.

35 A is the supporting-frame, having a leg portion B, made of any suitable metal. At the 40 apex of said leg portion is provided channel portions a a' a'', channel a extending inwardly and facing upwardly. Channel a' is vertical, facing inwardly, and channel a'' is vertical, facing outwardly. In the vertical channels 45 a' and a'' is placed a vertical standard D, secured therein by bolts passed through the standards and the perforations a³ a⁴ in channels a' and a'' in the leg portion; and in the horizontal channels a is placed a horizontal 50 cross-bar E, secured therein by bolts passed through the bar and the perforations a⁵ in the leg portion, thus forming a light, yet strong

and durable, supporting-frame for the tub F. As a pivotal support for the tub F, a conical spindle G is provided, having at its base a 55 plate b, integral with said spindle, by which the spindle is secured to the bar E, as shown. The bottom portion C of the tub F is perforated, as shown, and over and about said perforation is placed an inverted step-box J, and 60 below and about said perforation is placed a metal plate K, having a central perforation a⁶ to correspond with the central socket a⁷ in the step J; also, corresponding perforations for bolts by which the parts J and K are secured to the bottom of the tub; or, if preferred, the central portion of the box J may be lengthened and passed through the bottom of the tub from the under side upward through the bottom. The object sought is a 65 single central pin secured to the supporting-frame, with an inverted step-box secured to the bottom of the tub to rest upon and rotate about said pin as a pivotal support for the tub, thus avoiding the construction as well as 70 the cost of an intermediate oscillating frame 75 as a support for the tub.

A bifurcated bracket L is secured to one of the vertical posts D, the outer end portions of the prongs a⁸ a⁹ of which are parallel with 80 the outer face of the lever M. Trunnions b b² project inwardly from said prongs, and one of said trunnions has a screw-threaded engagement with its prong. The said trunnions fit in boxes b³, and by means of the threaded 85 trunnion all wear is compensated for, or the said latter trunnion may be screwed out of engagement with the box b³ and the lever may then be removed.

A connecting-rod box N, as shown in Fig. 8, 90 is formed of two similar parts, each having a body portion d', an angle wing portion d², outwardly-projected lugs d³, and a spherical box portion d⁴, the winged portions d² extending along the body portion d', and bolts, as d⁶, are 95 passed through the lugs d³, by which the parts are secured together, thus forming a spherical or ball-shaped box having an oblong opening d⁷ on its front side for the accommodation of a connecting-rod. One of these boxes is placed 100 at the lower end portion of the lever M for the rod O' and one at its upper end portion for the rod O, and they are secured thereto by bolts d⁸.

On the bottom portion of the tub F is secured a casting P, of the form substantially as shown in Figs. 5, 6, and 7, having a flat body portion, as h, by which it is secured to the 5 tub, and downwardly and inwardly projected flange portions h', forming slides, on which is placed a box-supporting plate Q, said plate having outwardly-projected wings h² to rest on the lower face of the flanges h', a body 10 portion h¹⁸ to slide between the flanges h' and a nut h⁴, the said nut projecting from the sides of the body portion over the inner face of the flange h', and is adjusted and secured in desired adjustments by turning the thumb-screw 15 h⁵, which has a shoulder b' to bear against the under face of the plate A, into the nut h⁴, thereby clamping the flanges h' between the wings h² of the slide P and the nut h⁴.

On the end of the plate a there is provided 20 a spherical box h⁶, in which is placed a ball-journal portion formed on the end of the connecting-rod O', thus forming a ball-and-socket joint, by which the connecting-rod is loosely secured to the bottom of the tub, a similar 25 ball on the other end of the connecting-rod resting in a similar box at the lower end of the actuating-lever M.

The rubber R is oscillated by the use of the arm S, secured to and projected from a vertical-shaft portion T, secured to the rubber R, and a connecting-rod O similar to the one hereinbefore described as O', said rod forming a ball-and-socket connection between the lever M and the arm S. The lower face of rubber 35 R may be provided with radial ribs h⁷.

A false bottom U is provided, which is secured to the tub by arms V. The upper face of the bottom U is provided with radial ribs h⁸. The arms V are bifurcated, as shown, 40 forming prongs k, and the lower ends of said prongs are secured to the bottom U a short distance apart. The arms V are situated diametrically opposite each other or thereabout. The upper end portion is provided 45 with a handle portion k' and an oblong perforation k². A hook k³, that will pass through the perforation k², is provided, which is turned by a turn-button k⁴ on the outside of the tub. The prongs secured to the false bottom serve 50 to hold the bottom in position, rendering the usual means employed to secure the false to the permanent bottom unnecessary. I wish to call particular attention to the convenience and economy of this feature of construction, 55 as by the use of the arms V, secured as they are to the false bottom and to the sides of the tub, said bottom is securely held in position during the operation of the machine in washing, and by releasing the arms from the sides 60 of the tub by the use of the turn-button k⁴ the hook k³ may be passed through and out of the perforations k², thus releasing the arms V, by which the bottom U with the wash may be removed from the tub. Heretofore hooks 65 and staples have been used to secure the bottom U to the bottom of the tub, which were hooked and unhooked by thrusting the hands

down through the hot water and with the fingers between the said bottoms operate the hooks.

To remove the rubber R from the tub, the bolt h⁵ at the end portion of the cross-bar W is released from its connection with the standard D and the bar with the rubber raised out and supported by the hinged connection 15 75 to the supporting-frame A.

I will now call particular attention to the operating parts of the machine. It will be noticed that the distance on the lever M from the fulcrum Z, formed by the bracket L, to the connecting-rod box N' is less than the distance from said fulcrum to the connecting-rod box N, by which arrangement the rotary movement of the rubber R is greater than the rotary movement of the tub, and thus the 80 85 greater power is applied to the movement of the tub and its burden.

In operation the lever M is reciprocated back and forth, thus imparting to the tub and rubber R opposite rotary movements, as 90 is common in machines of this class, and by this action the clothes are rapidly and thoroughly cleansed.

Having thus fully described the nature and object of my invention, what I claim as new, 95 and desire to secure by Letters Patent, is—

1. The combination, in a washing-machine, of a tub F, supporting-frame A, having metal leg portions B, provided with channel portions a, a', and a², in which are secured a cross-bar E and standards D, substantially as described, and for the purpose set forth.

2. The combination, in a washing-machine, of a tub-supporting frame having leg portions B, as described, a cross-bar E, and standards D, of a spindle G, secured to said cross-bar, a tub having a central perforation in its bottom portion, an inverted step-box J, secured over said perforation, and a perforated plate K, secured about said perforation, the two parts J and K secured to said bottom portion and together, an actuating-lever M, pivotally secured to said frame and connected to tub, whereby said tub may be turned on its pivot, substantially as set forth.

3. In combination with the tub F, a false bottom U, bifurcated arm V, provided at their lower end portions with prongs k, spread apart a distance, and said arms V secured to said bottom diametrically opposite, or thereabout, and each formed at its upper end portion with an aperture k² and a handle portion k', and a turn-button or hook to take into said aperture, by which the arms may be removably secured to the tub to hold the false bottom in rigid relation to the tub when in operation or to raise the said bottom out of the tub, substantially as described, and for the purpose set forth.

4. The combination, with the supporting-frame and tub, of a lever-supporting bracket L, secured to said frame, an actuating-lever M, pivotally secured in said bracket, connecting-rod box N', having a body portion d', an-

- gle wing portion d^2 , lugs d^3 , and a spherical box portion d^4 , a connecting-rod O' , having spherical end portions, a casting P , secured to the bottom of the tub, as shown, and a plate 5 Q , which has a spherical box h^6 , a nut h^7 , and a thumb-screw h^8 , by which the plate may be removably secured to the casting P , substantially as described, and for the purpose set forth.
- 10 5. The combination, with the supporting-frame A , having a tub F pivotally secured thereto, of a lever-supporting bracket secured

to said frame and having outwardly-projecting arms a^8 and a^9 and inwardly-projecting trunnions, one of which is made adjustable, a lever engaged between said trunnions, and a rod connecting said lever to said tub, substantially as set forth.

In testimony whereof I have hereunto set my hand this 29th day of July, A. D. 1889.

BENJAMIN BROBST.
